M. Mattson.
Bath.

No 35,458.

Patented Jun. 3, 1862.

UNITED STATES PATENT OFFICE.

MORRIS MATTSON, OF BOSTON, MASSACHUSETTS.

IMPROVEMENT IN DOUCHE BATHS.

Specification forming part of Letters Patent No. 35,458, dated June 3, 1862.

To all whom it may concern:

Be it known that I, MORRIS MATTSON, of Boston, in the county of Suffolk and State of Massachusetts, have invented a Changeable Spray or Douche Bath, of which the following is a full, clear, and exact description, reference being had to the accompanying drawing, making part of this specification, in which the figure represents a suitable apparatus for carrying out my invention.

In administering baths for the treatment of disease it is necessary that the temperature of the bath should be completely under control. This is particularly requisite when administering spray or douche baths, which are generally applied for the purpose of rousing and increasing the action of the skin and stimulating the smaller blood-vessels at or near the surface. The degree of cold which may thus be applied with safety and comfort to one patient will give a shock which may be not only disagreeable, but dangerous, to another. For this reason it is frequently desirable to commence the spray or douche bath at a moderately warm temperature and gradually lower the temperature. The bath may thus be more safely applied at a lower degree and a better reaction be produced, increasing its curative effects; or warm and cold sprays or douches may be made to alternate one with the other.

The object of my present invention is to produce a bath of this description which may be easily regulated and which will be entirely under control as regards the temperature at which it is applied to the patient; and my invention consists of a bath in which two or more tanks or reservoirs for containing water of different temperatures are employed, the outlets from which unite in one delivery-pipe and are commanded by a suitable cock or cocks, by which the temperature of the water delivered to the bather may be readily and nicely adjusted.

That others skilled in the art may understand and use my invention, I will proceed to describe the manner in which I have carried it out.

In the said drawing, A and B are two tanks, the water in each of which is maintained at the required temperature by drawing into them from hot and cold water faucets or other

convenient method. On a platform, C, over these tanks is placed a force-pump, D. (I prefer one which will throw a steady stream.) To the suction-pipe c of this pump is connected a pipe, a, from the tank A, and another, b, from the tank B, each of which is of the same diameter as the pipe c. A hose, d, is attached to the nozzle of the pump, so that the attendant while pumping may direct the stream upon the patient. (When a spray is required, a rose is attached to the end of the hose.) A cock operated by a lever, e, commands the pipe a, and another one operated by a lever, f, commands the pipe b. Graduated scales to which these levers point indicate the positions of the cocks, the marks on the scales being so arranged that when one cock is entirely open the other shall be closed. The capacity of the suction-pipe of the pump and of the pipes from each tank being the same, the portion of water delivered to the pump from each tank may be varied, and yet the pump will always receive a sufficient supply. For example, the cock of the pipe a may be open one-quarter and the cock of the pipe b may be opened three-quarters. For the convenience of the attendant the levers e and f may be connected by a rod, so that they may be moved simultaneously; or a single three-way cock may be placed at the intersection of the three pipes a, b, and c, when the movement of a single lever would regulate the temperature of the water delivered by the pump, the water from the two tanks being mingled in the desired proportions, a scale showing the proper position at which to place the lever.

I have described above one way of carrying out my invention; but as other methods may be employed I do not wish to confine myself to the use of the force-pump D and hose d for throwing the water upon the patient. For example, where the tanks or reservoirs can be so placed as to give a sufficient head of water at the delivery-pipe, it will only be necessary to adjust the cock or cocks which regulate the flow of water from each reservoir into the delivery-pipe, and the same arrangement of pipes and cocks may be adopted when one of them is connected with the street-main (in cities) and the other proceeds from a boiler or heater.

What I claim as my invention, and desire to secure by Letters Patent, is—

A bath apparatus consisting, essentially, of two or more tanks or reservoirs containing water of different temperatures, the outlets from which unite in one delivery-pipe and are commanded by a suitable cock or cocks, sub-

stantially in the manner specified, for the purpose specified.

MORRIS MATTSON.
